Solomon C. Batchelor and Nelson S. Thomas of Watertown, N.Y.
Letters Patent

The Schedule referred to in these Letters Patent and making part of
the same containing a description in the words of the said Solomon
C. Batchelor and Nelson S. Thomas themselves of their improve-
ment in framing joints in wood work.

To all to whom these presents shall come: Be it known that we
Solomon C. Batchelor and Nelson S. Thomas of Watertown in the
County of Jefferson and State of New York, have invented a new
and useful improvement in framing joints in wood work such as
Bridgsteads, Machine frames &c when a rail or other named hor-
izontal pieces may be framed and secured at right angles, on two
or more sides into an upright post on the same level, and that
the following is a full and exact description thereof.

The tenon is framed by a dove tail on one edge the other edge
being straight and on a line with the face of the timber or rail.
The shoulder on the dove tail edge should be of the dimensions
of nearly half the diameter or measure of the peg which is to hold
the tenon after it is inserted in the mortise. The mortise after being
bored out of nearly the dimensions of the tenon is to have added to
it the size of the key hole, which key hole is to be on the straight edge
of the tenon and must be so laid out that the smallest end shall
have half its dimensions or diameter above or below as the case may
be. The faced edge of the tenon the whole being bored on such bent
as to be laid out on the opposite side of the post in full
dimensions above or below as the case may be. The line of the faced edge
of the tenon. Should be framed the rail into a post at right angles
the dove tail of the tenon is secured, the mortise being a little man-
euvered. The mortise will be beat till the nail may be in the
post and the length of the tenon made accordingly. The key hole
should be bored before the mortise is beat. When rails enter a post
opposite each other the tenons should be laid out so as to come

158.

on opposite sides of an imaginary line in the post. The joints are to be secured by keys, the round key flattened at one end so as to fill the hole above (or below) the tenon or the most preferable.

What we claim is, an invention and not previously known in the above description is being able to frame and secure by means of keys, right angled corners where the rails or timbers are on the same level, to whatever material metal or wood. We also claim whatever variation where the same principle is involved.
